UNITED STATES PATENT OFFICE.

WILLIAM C. FISK, OF TOLEDO, OHIO.

SPRAY-OIL BURNER.

SPECIFICATION forming part of Letters Patent No. 399,864, dated March 19, 1889.

Application filed June 14, 1888. Serial No. 277,066. (No model.)

To all whom it may concern:

Be it known that I, WILLIAM C. FISK, a citizen of the United States of America, residing at Toledo, in the county of Lucas and State of Ohio, have invented certain new and useful Improvements in Spray-Oil Burners; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in apparatus for burning crude oil, the object thereof being to provide a means whereby steam may be utilized to raise the oil by producing a vacuum in a chamber, and will carry the oil, intermixed with steam and air, in the form of spray under a boiler, so that it can be burned; and it consists more especially in the construction and combination of the parts, as will be hereininafter fully set forth, and specifically pointed out in the claims.

In the accompanying drawings, Figure 1 is a sectional view, and Fig. 2 a sectional view taken through the line $x-x$ of Fig. 1.

30 A refers to a connection coupling thereto a steam-pipe, which may communicate directly with a boiler or other source for generating steam.

B is a similar coupling connected to a pipe which leads to an oil-tank, which may be located at any suitable distance from the boiler, said oil tank or barrel being preferably placed underground.

40 C refers to the burner through which the spray is injected so as to be ignited under the boiler, said burner being supported in any suitable manner by the boiler or furnace walls.

D refers to a casting which is provided with externally-screw-threaded portions a , b , and c , by means of which the pipes A and B are attached thereto, and the end of the casting is supported centrally within the opening in the burner C, said burner at its outer end having a transverse internally-screw-threaded bar.

45 50 One end of the casting D is provided with a projection, e , having external screw-threads, e' , to which is attached a cap, E, which car-

ries a conical valve, F, having a suitable handle, so that by turning the same the valve-stem can be moved to and from its seat. The 55 valve-stem F passes through a steam-chamber, G, which is connected by a passage-way, H, with the steam-pipe. This passage-way H also communicates with an auxiliary steam-chamber, G', when the valve I is open. The 60 valve I is a simple turn-valve having a cut-away portion for connecting the passage-way H with the chamber G' and for cutting off said chamber from the passage-way when desired. The casting D is provided with walls 65 i , i' , and i'' , the openings in the walls i and i' being internally screw-threaded for the reception of tubular plugs K and L. The steam or jet plug K is seated in the forward end of the steam-chamber G, and has a valve-seat 70 formed thereon, at the base of which there is a conical opening, and the mixing-plug L, leading from oil-chamber m to the injector tube or nozzle D', has a conical opening at the end adjacent to plug K, and from thence a 75 straight-way opening. The walls i and i' , with the other portions of the casting, form oil-chamber m and air-chamber n , the chamber n being provided to one side with an opening which communicates with the air, 80 and which may be covered or closed by an ordinary turn-button, N, as shown in Fig. 2. The plug L, which is supported by the walls i' and i'' , is provided within the chamber n with openings or perforations n' , communicating therewith, through which the air from the chamber can pass when the turn-button N is removed from the opening in said chamber.

The proportions and relative arrangement 90 of the parts are substantially as shown in the accompanying drawings.

The end of the casting D, forming the injector tube or nozzle D', through which the oil, steam, and air intermixed with each other 95 are injected into and through the burner, extends within the burner C, and the mixing tube or plug L projects into the end of the casting supported by the burner.

The operation of my invention is as follows: 100 Steam is admitted through the pipe A, and from thence to the steam-chamber G through passage-way H. The valve-stem F being slightly removed from its seat, the steam will

pass through the steam or jet plug K and through the mixing-plug L into the burner, creating a vacuum in the oil-chamber m, so as to elevate the oil and carry it mixed with the steam to the burner. When the turn-button N is removed from the opening leading to the air-chamber, a certain amount of air will be drawn in said chamber and mixed with the oil and steam. When the valve I is turned, a portion of the steam will pass around the opening of said valve and enter the auxiliary steam-chamber G', and, passing around the end of the plug L, will impel the oil mixed with the steam and air forwardly into the burner. A sufficient quantity of air will be drawn into the conical end of the burner to supply the combustion with oxygen. The device can be regulated by turning the valves so as to mix the oil, steam, and air in different proportions, as desired. By this device the oil can be raised to a great height or drawn from receptacles placed in cellars and away from the furnace, so there is no danger of the same becoming ignited. The end of the plug L, which is formed substantially into a tube, forces and sprays the oil, and the air-inlets tend to separate the oil.

I am aware that prior to my invention it has been proposed to use oil as fuel by intermixing the same with steam and air and injecting the same into a furnace where it is burned, and I do not claim such construction, broadly, as my invention; but

What I do claim as new, and desire to secure by Letters Patent, is—

1. An injector-burner for hydrocarbon-furnaces, consisting of a casing communicating with oil and steam supply pipes, a steam-chamber and auxiliary steam-chamber arranged at opposite ends of the casing, a passage connecting the steam-chambers with the steam-supply, a valve to close communication between the auxiliary steam chamber and passage, an oil-chamber in direct communication with the oil-supply, a tubular jet-plug connecting the steam and oil chambers, an injector tube or nozzle leading from the auxiliary steam-chamber, a mixing-tube leading

from the oil-chamber to the injector-tube, and a valve adapted to close the inlet end of the jet-plug, substantially as described.

2. An injector-burner for hydrocarbon-furnaces, consisting of a casing communicating with oil and steam supply pipes, a steam-chamber at one end of the casing, connected by a passage with the steam-supply, an oil-chamber communicating directly with the oil-supply, a tubular jet-plug connecting the steam and oil chambers, an air-chamber adjoining the oil-chamber, an injector-tube, a mixing-tube leading from the oil-chamber to the injector-tube and provided with lateral openings communicating with the air-chamber, a valved opening in the side of the air-chamber, and a valve adapted to close the inlet end of the plug, substantially as described.

3. In a device of the character described, the combination of a casing communicating with oil and steam supply pipes, a steam-chamber and auxiliary steam-chamber at opposite ends of the casing, a passage connecting the steam-chamber with the steam-supply, a valve to close communication between the auxiliary steam-chamber and passage, an oil-chamber communicating directly with the oil-supply, an air-chamber between the oil and auxiliary steam chambers having an opening in its outer wall, an open burner-tube flared at one end and projecting at its other end within a furnace, an injector-tube leading from the auxiliary steam-chamber and having its discharge end secured centrally within the flared end of the burner-tube, a mixing-tube extending from the oil-chamber to the injector-tube and provided with lateral openings communicating with the air-chamber, a valve or turn-button to close the opening in the wall of the air-chamber, and a valve adapted to close the inlet end of the jet-tube, substantially as described.

In testimony whereof I affix my signature in presence of two witnesses.

WILLIAM C. FISK.
